COMBINED DISPLAY AND COIN CONTROLLED DISPENSING CABINET FOR NEWSPAPERS

Ronald W. Yeo, 604 Iris, Corona Del Mar, Calif. 92625

Filed Sept. 18, 1968, Ser. No. 13,591

Term of patent 14 years

Int. Cl. D20—01

U.S. Cl. D52—3

FIG.1

FIG.2

FIG.3

FIG.4

FIG.5

FIG. 1 is a front perspective view of a combined display and coin controlled dispensing cabinet for newspapers showing my new design;

FIG. 2 is a rear elevational view thereof;

FIG. 3 is an elevational view, taken from the left side thereof;

FIG. 4 is an elevational view, taken from the right side thereof; and

FIG. 5 is a top plan view thereof.

The broken line representations of a newspaper in FIG. 1 are for purposes of illustration only.

I claim:

The ornamental design for a combined display and coin controlled dispensing cabinet for newspapers, substantially as shown and described.
